ANCHOR FOR TAPES, BANDS, CABLES,
AND THE LIKE

George Steingruber, Atlanta, Ga.

Application January 13, 1949, Serial No. 70,701

4 Claims. (Cl. 16—202)

1

The present invention relates to anchors for tapes, bands, cables and the like, and more especially, to a new and improved screwless anchor for securing stainless steel or other suspension tapes, bands or flat cables to window sashes.

In my prior application Serial No. 44,679, filed August 17, 1948, I have disclosed a novel and improved counterbalancing mechanism for window sashes, said counterbalancing mechanism having the general form of a spring-actuated counterbalance shaft carrying pulleys or drums about which flexible stainless steel flat cables, tapes or bands (generally referred hereinafter as cables) are wound, with the opposite ends of the cables attached to the window sash so as to support the sash at any position of vertical adjustment in the window frame.

The present application is directed to the anchoring means per se for attaching the cables to the window sash, said anchoring means having for its principal objects to provide a simple, effective and inexpensive anchor by which a cable can be quickly and easily attached firmly to the window sash or detached therefrom, at will, without the aid of screws or other fastenings requiring penetration and consequent weakening of the cable.

Other and further objects and advantages of the invention will be hereinafter described and the novel features thereof defined in the appended claims.

In the drawing:

Figure 1 is a fragmentary view, partly in vertical section and partly in elevation, showing a typical application of my new cable anchor to a window structure of the vertically sliding sash type, with the anchor and cable shown in end elevation;

Figure 2 is a transverse sectional view taken on the line 2—2 of Figure 1; and

Figure 3 is a fragmentary perspective view, showing the cable anchor applied to one of the upper corners of the window sash, with the cable omitted.

Like reference characters designate corresponding parts in the several figures of the drawing, wherein 1 generally denotes a window structure of the double-hung, vertically sliding sash type, said window structure being equipped with sash balancing means of the type disclosed in my prior application hereinbefore referred to. Only a portion of the window structure is illustrated in Figure 1, but said portion includes one sash, designated 2, which is vertically slid-

able in a channel 3 of the window frame which is generally indicated at 4, it being understood that in the case of a double-hung window, the window frame is provided with two sashes, each sliding in a separate channel. For the purposes of the present invention, it is sufficient to illustrate only that portion of the window structure which includes one of the sashes.

While the window structure as illustrated is typically constructed largely of metal, it is to be understood that the present invention is not confined to window structures of the metal type, since it is equally applicable to conventional window structures of wood, or partly of wood and partly of metal.

The sash balance mechanism for the sash 2 is generally indicated at 5, but the complete details of this mechanism are immaterial to the present invention. A more complete explanation of the details of this mechanism may be had from reference to my prior application aforesaid, and for the purposes of the present application, I have illustrated only those elements which directly concern the suspension of the window sash 2 in the sash channel 3 by means of one or more flexible stainless steel flat cables, bands or tapes designated 6. In the preferred construction, each sash is suspended by two cables 6 located respectively at the opposite sides of the window frame, the upper ends of each cable being wound about a drum or pulley 7 carried by and fixed on a transversely extended counterbalance shaft 8. The lower end of each cable 6 is suitably attached to the upper corner of the sash, and the present invention more particularly concerns a novel and improved anchor for anchoring the lower end of the cable 6 to the sash, without the aid of screws or other fastenings which penetrate the cables and tend to weaken the cable or otherwise reduce the effective life thereof.

As indicated in the several figures of the drawing, my improved anchor has the form of a laterally extended plate member generally designated 9 which is suitably fixed to the upper edge of the sash 2 near the corner thereof, as by means of a screw 10, or other appropriate fastening. The laterally extended marginal edges of the plate 9 are disposed parallel to each other for the major portion of their length, and are preferably turned upwardly to form flanges 11, 11, which serve to stiffen and reinforce the plate. The outer end of the plate 9 is provided with a laterally extended slot 12 which leads from the extreme end of the plate inwardly for a distance

at least equal to the width of the cable 6. This slot 12 is disposed substantially parallel to the laterally extended marginal edges of the plate 9 and is located intermediate said edges, but preferably somewhat closer to one edge than the other. It will be further noted from the drawing that at least those portions of the flanged marginal edges 11, 11 of the plate 9 which are in transverse registry with the slot 12 are smoothly curved or rounded and are wholly devoid of sharp corners, as indicated at 13, 14, and one of the edges, namely, the edge 13, is transversely offset somewhat beyond the flange 11 at the corresponding side of the plate 9.

In attaching the cable 6 to the sash 2 by means of the anchor member or plate 9, the cable is extended transversely across the bottom of the plate at the slotted end thereof from one extreme marginal edge to the other. The extreme free end of the cable is then looped about the forward edge of the plate and then is extended downwardly through the slot 12 and thence between the bottom face of the plate and the underlying advance portion of the cable, back to the first marginal edge of the plate. Any excess or surplus end of the cable remaining may be bent over so as to lie flat against the upper face of the plate, as indicated at 15. The opposite edges of the slot 12 are preferably inclined in the direction of lead of the cable to prevent cutting of the cable.

By the use of an anchor constructed and arranged as above described, the cable 6 can be quickly attached to the sash 2 or detached therefrom, at will, and when so attached, the greater the tensile strain upon the cable, the greater will be the gripping effect tending to clamp the extreme free end of the cable between the plate 9 and an advance portion of the cable ahead of the slot 12, with consequent increase in frictional contact and anchoring effect on that portion of the cable which is looped about the forward edge of the plate.

I have found from actual use of anchors constructed in accordance with the present invention that the cables will remain firmly attached to the window sash without any tendency of slippage or accidental detachment, and are capable of sustaining weights up to the maximum tensile limits of the cables.

Instead of employing separate anchor plates of the form illustrated in the drawing, the same results can be obtained by forming the anchor as an integral part of the upper edge of the window sash, particularly where the sash is made of metal. In any case, it is advisable to eliminate all sharp corners wherever the cable makes an abrupt turn or bend about the anchor, in order to minimize chafing or accidental cutting of the cable.

Other uses of my improved anchor will readily suggest themselves to those skilled in the art, and it is to be understood that my invention is not limited in its application to the anchorage of cables to window sashes. While the specific details have been herein shown and described, the invention is not confined thereto as changes and alterations may be made without departing from

the spirit thereof as defined by the appended claims.

I claim:

1. An anchor for flat members such as cables, tapes, bands and the like, comprising a laterally extended anchor plate member having a laterally extended slot in one end thereof extending to the extreme lateral end of the plate member so as to be open at one lateral end of the plate member, said slot being of a length at least equal to the width of the flat member, said slot being located between and disposed substantially parallel to the laterally extended marginal edges of the plate member, the slotted end of said plate member being arranged to receive one end of the flat member beneath the same, with the flat member extended from one lateral marginal edge to the other and then reversely folded about the latter edge and across the upper face of said plate member to said slot, then downwardly through the slot and across the lower face of said plate member between the plate member and the first-mentioned underlying portion of said flat member, to the first-mentioned lateral marginal edge of the plate member.

2. An anchor as defined in claim 1, wherein the opposite edges of the slot are inclined in the direction of the lead of the flat member, said edges of the slot being in parallel spaced relation to each other, the space therebetween being only slightly greater than the thickness of the flat member.

3. An anchor as defined in claim 1, wherein the laterally extended marginal edges of the plate member are extended outwardly from one face of the plate member to form marginal flanges.

4. An anchor for flat members such as cables, tapes, bands and the like, comprising a laterally extended anchor plate member having a laterally extended slot in one end thereof, said slot being located between and disposed substantially parallel to the laterally extended marginal edges of the plate member, the flat member-engaging portion of one of said laterally extended marginal edges of the plate member being transversely offset beyond the remainder of said edge, the slotted end of said plate member being arranged to receive one end of the flat member beneath the same, with the flat member extended from one lateral marginal edge to the other and then reversely folded about the latter edge and across the upper face of said plate member to said slot, then downwardly through the slot and across the lower face of said plate member between the plate member and the first-mentioned underlying portion of said flat member, to the first-mentioned lateral marginal edge of the plate member.
